UNITED STATES PATENT OFFICE

147,498

DESIGN FOR A COMBINATION ELECTRIC TOASTER, STORAGE COMPARTMENT, AND SUGAR AND CREAM CONTAINERS

William Flajole, Detroit, Mich.

Application January 23, 1946, Serial No. 125,858

Term of patent 7 years

(Cl. D81—10)

To all whom it may concern:

Be it known that I, William Flajole, a citizen of the United States, residing at Detroit, in the county of Wayne and State of Michigan, have invented a new, original, and ornamental Design for a Combination Electric Toaster, Storage Compartment, and Sugar and Cream Containers, of which the following is a specification, reference being had to the accompanying drawing, forming part thereof, in which:

Fig. 1 is a perspective view of a combination electric toaster, storage compartment and sugar and cream containers, embodying my new design,

with the sugar and cream containers shown in Fig. 2 removed; and

Fig. 2 is a similar view thereof but with the sugar and cream containers in place.

The peripheral walls of the toaster, not shown, are substantially plain.

I claim:

The ornamental design for a combination electric toaster, storage compartment, and sugar and cream containers, substantially as shown and described.

WILLIAM FLAJOLE.
